United States Patent Office

Des. 232,786

Patented Sept. 17, 1974

232,786

BUTTON TOPPER OR SIMILAR ARTICLE

Clarence D. Marer, Johnston, R.I., assignor to Swank, Inc., Attleboro, Mass.

Filed May 22, 1972, Ser. No. 255,952

Term of patent 14 years

Int. Cl. D2—07

U.S. Cl. D2—451

FIG. 1 is a top plan view of a button topper or similar article, showing my new design;

FIG. 2 is a bottom plan view thereof;

FIG. 3 is a side elevational view thereof; and

FIG. 4 is a front elevational view thereof.

I claim:

The ornamental design for a button topper or similar article, as shown.
